We claim the ornamental design for an information handling system, as shown and described.

DESCRIPTION

FIG. 1 is a front perspective view of the information handling system comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof; and,

FIG. 8 is a front open perspective view thereof.

The even-dash broken lines shown in the drawings represent portions of the information handling system, and form no part of the claimed design. The dash-dot broken lines adjacent to the shaded areas are boundaries of the claimed design and form no part thereof.
